CARPET SWEEPER CASE AND DUSTPAN
CONSTRUCTIONHerbert C. Dilliard, East Bangor, Pa., assignor to
Bissell Carpet Sweeper Company, Grand
Rapids, Mich.

Application April 6, 1936, Serial No. 72,879

2 Claims. (Cl. 15—41)

This invention has for its objects:

First, to produce a new and improved carpet
sweeper dust pan and casing construction.Second, to produce such a construction in
5 which the dust pans are removable to facilitate
dumping of the sweepings therefrom and to facilitate
the inspection and repair of the rest of the
carpet sweeper.Third, to provide such a construction in which
10 the dust pans are removable through the top of
the casing and have sections forming a portion of
the top of the casing whereby a sweeper of nice
appearance is provided.Further objects and advantages pertaining to
15 details and economies of construction and operation
will appear from the description to follow.
Preferred embodiments of my invention are illus-
trated in the accompanying drawing, in which:Fig. 1 is a sectional view through a carpet
20 sweeper embodying my invention.Fig. 2 is a detail sectional view taken on line
2—2 of Fig. 1.Fig. 3 is a perspective view of a dust pan made
in accordance with my invention.25 Fig. 4 is a detail sectional view of a slightly
modified type of a dust pan in place in a carpet
sweeper casing.Fig. 5 is a perspective view of a still different
modified form of dust pan for a carpet sweeper.30 In the drawing, 1 is a carpet sweeper casing
which has therein a brush 2 of usual construc-
tion which is provided with a hub 3 which engages
the floor wheels 4 of the sweeper. These floor
35 wheels 4 are provided at each end of the sweeper
and have axles 5 extending through the casing
parallel to the brush. The casing consists of a
top member 6 which has openings 7 therein for
the introduction and removal of the dust pans 8.30 In the drawing Figs. 1-3, I show a type of dust
40 pan made of sheet metal. The dust receiving
portion 9 extends parallel with the brush and has
a lip 10 which extends over the through axles 5
and into proximity to the brush 2. An opening 11
parallel with the brush is provided for the sweep-
45 ings to pass into the portion 9 of the dust pan.
The dust pan is fastened to a section 12 of the
top of the sweeper casing which section fills the
opening 7 and provides a continuation of the top
50 of the sweeper casing. The section 12 is provided
with a hole 13 for the insertion of a finger for
removal of the dust pan which is lifted out
through opening 7 and the dust pan is provided
55 with a sheet metal portion 14 which extends under
the opening 13 and is fastened as at 15 and 16 to
the section 12, providing a well into which afinger may be inserted and providing a cover
through which the sweepings from the dust pan
8 will not pass.In the modification of the device shown in
Fig. 4, I provide a dust pan 108 having a portion 5
109 for receiving the sweepings. A sheet metal
top 112 is provided which fits over the opening 107
in the top of the sweeper casing and seals the
opening, the portion 112 of the dust pan forming
15 a continuation of the top 106 of the sweeper casing.
A guide 118 is provided which extends over the through axle 5 of the sweeper casing
and to a point adjacent the brush 2. This guides
the sweepings from the brush over into the dust
pan 108. A depression 113 is provided in the 20
top portion 112 of the dust pan and a handle 17
is provided in said well for removal of the dust
pan. The sweepings pass into this dust pan
through the opening 111. In Fig. 5 I show a still
25 different modification of structure embodying
features of the structure shown in Figs. 1 to 3
and the structure shown in Fig. 4. The top of the
pan shown in Fig. 5 at 112 is the same as the
top 112 of the pan structure of Fig. 4, and has a
30 depression 113 the same as the depression in
the structure of Fig. 4, and a handle 17. The
end wall differs from the end wall of the structure
of Fig. 4 in that it has an opening 18 therein
35 for dumping the sweepings from the pan instead
of dumping them through the opening 211 there-
in through which they pass to the pan. In the
structure of Fig. 5 the bottom is constructed sub-
stantially the same as the structure of Figs. 1 to 3
and the member 210 is substantially the same as
the member 10 in the structure of Figs. 1 to 3 35It will be appreciated that with my construc-
tion the dust pan may be removed from the
sweeper for dumping and the awkwardness of
having to carry the whole sweeper and hold it
40 while dumping it is eliminated. At the same time
it is possible to remove the dust pans which facili-
tates access to the other parts of the sweeper for
inspection or repair.Having thus described my invention, what I
45 claim as new and desire to secure by Letters
Patent is:1. In a carpet sweeper having a casing, an
elongated rotary brush therein, and floor wheels
with an axle extending through the casing, the
50 combination of a removable dust pan disposed
parallel with said brush, a guide extending up-
wardly from adjacent said brush over said axle
and to said pan, said pan having an opening to
receive sweepings passing over said guide from
55 said brush, the top of said casing having an

opening for the removal of said dust pan and said dust pan having a top closing said opening and forming a portion of the top of the casing when said pan is in position in said casing.

- 5 2. In a carpet sweeper having a casing, and an elongated rotary brush therein, the combination of a casing top having a removable section extending parallel with and along one side of the brush, a hole in said section for the insertion of

fingers for the removal of said section, and a sheet metal dust pan fastened to the bottom of said section and having a metal member extending under said hole and spaced from the bottom of said removable section, said dust pan extending parallel with said brush and having an opening to receive sweepings from said brush. 5
